Primary Examiner — George J Ulsh*Assistant Examiner* — Bethany Louise Mallino(74) *Attorney, Agent, or Firm* — John Rizvi; John Rizvi, P.A.—The Patent Professor ®(57) **CLAIM**

The ornamental design for a mesh A.C. cover as shown and described.

DESCRIPTION

FIG. 1 is a perspective view of a mesh A.C. cover on an A.C. unit showing my new design;

FIG. 2 is an isometric view of thereof;

FIG. 3 is a top plan view thereof.

FIG. 4 is a zoomed top orthogonal view showing a break and separation at "A" of the repeating inner portion of the design thereof; and,

FIG. 5 is a side view of FIG. 4.

A design bottom plan view has been omitted, as the bottom of the design is the same as the top plan view of FIG. 3.

A design rear, left, and right elevation views have been omitted, as they are the same as the front elevation view of FIG. 5.

The portion of FIG. 1 depicting an environmental A.C. unit and ties in broken lines forms no part of the claimed design.
